US00D800593S

(12) **United States Design Patent** (10) **Patent No.:** **US D800,593 S**
(45) **Date of Patent:** **** Oct. 24, 2017**

(54) **RECEPTACLE OF A BAND FOR A WEARABLE FITNESS BAND SYSTEM**

(71) Applicant: **Fitbit, Inc.**, San Francisco, CA (US)

(72) Inventors: **Kenneth S. M. Ling**, San Francisco, CA (US); **Alexander Joseph Ringrose**, Oakland, CA (US); **Patrick James Markan**, San Francisco, CA (US)

(73) Assignee: **Fitbit, Inc.**, San Francisco, CA (US)

(**) Term: **15 Years**

(21) Appl. No.: **29/563,191**

(22) Filed: **May 3, 2016**

Related U.S. Application Data

(63) Continuation of application No. 29/553,318, filed on Jan. 29, 2016, which is a continuation-in-part of application No. 29/521,264, filed on Mar. 20, 2015, now Pat. No. Des. 759,516, which is a continuation-in-part of application No. 29/520,607, filed on Mar. 16, 2015, now abandoned.

CLAIM

We claim the ornamental design for a receptacle of a band for a wearable fitness band system, as shown and described.

DESCRIPTION

FIG. 1 is an off-angle view of a receptacle of a band for a wearable fitness band system.

FIG. 2 is a front view of the receptacle of a band for a wearable fitness band system of FIG. 1.

FIG. 3 is a top view thereof.

FIG. 4 is a bottom view thereof.

FIG. 5 is an off-angle bottom view thereof, shown with section lines indicating sectioning planes for FIGS. 6-9.

FIG. 6 is a removed section view taken along lines 6-6 of FIG. 5.

FIG. 7 is another removed section view taken along lines 7-7 of FIG. 5.

FIG. 8 is a further removed section view taken along lines 8-8 of FIG. 5.

FIG. 9 is an additional removed section view taken along lines 9-9 of FIG. 5.

FIG. 10 is an off-angle section view of the receptacle of a band for a wearable fitness band system of FIG. 6, taken along the lines 6-6 of FIG. 5, shown with a symbolic break line.

FIG. 11 is another off-angle section view of the receptacle of a band for a wearable fitness band system of FIG. 6, taken along the lines 6-6 of FIG. 5, shown with a symbolic break line.

FIG. 12 is yet another off-angle section view of the receptacle of a band for a wearable fitness band system of FIG. 6, taken along the lines 6-6 of FIG. 5, shown with a symbolic break line; and,

FIG. 13 shows an off-angle view of the receptacle of a band for a wearable fitness band system of FIG. 1.

The receptacle of a band for a wearable fitness band system shown in the accompanying figures is recessed into the band so the band obscures the receptacle in the side and rear views and such views are therefore not shown. However, cutaway and section views of the receptacle portion are provided to better depict the ornamental design of the receptacle of a band for a wearable fitness band system.

The stipple shading shown in the drawings is to indicate surface contours and not texture. The broken lines and non-shaded areas illustrate environmental structure which forms no part of the claimed design. In FIGS. 10-12, solid lines with a lighter line weight are used to indicate tangent edges of the claimed design and provide better understanding as to the contours of the claimed design. It is to be understood that such lighter-weight solid lines are not actually part of the ornamental design, but are merely provided as a visual aid to allow better understanding of the contours in the ornamental design.

The dash-dot-dash lines shown in the drawings illustrate the bounds of the claim and form no part of the claimed design.
